The ornamental design for a through-the-wall recycling bin, as shown and described.

DESCRIPTION

FIG. 1 is a perspective view showing a through-the-wall recycling bin embodying my new design;

FIG. 2 is a front elevational view thereof;

FIG. 3 is a right side elevational view thereof;

FIG. 4 is a bottom plan view thereof;

FIG. 5 is a top plan view thereof;

FIG. 6 is a left side elevational view thereof; and,

FIG. 7 is a rear elevational view thereof.

The broken lines are for illustration only, and form no part of the present invention.
